CAMILLE DE VLEESCHOUWER AND JOHANNES TACOMA, OF AMSTERDAM, NETHERLANDS.

LATCH MECHANISM FOR COLLAPSIBLE SHELVES AND DOORS.

1,214,018.

Specification of Letters Patent. Patented Jan. 30, 1917.

Application filed July 23, 1914. Serial No. 852,628.

To all whom it may concern:

Be it known that we, CAMILLE DE VLEESCHOUWER and JOHANNES TACOMA, subjects of the Queen of the Netherlands, the former 5 residing at Amstelveensche Weg 139, and the latter residing at Nieuwe Zijds Voorburgwal 227, both in Amsterdam, in the Kingdom of the Netherlands, have invented certain new and useful Improvements in Latch Mechanism for Collapsible Shelves and Doors, of which the following is a specification, reference being had to the drawings hereto annexed and to the figures and letters marked thereon—that is to say:

15 The present invention relates to latch mechanisms and particularly to mechanisms for automatically securing doors, collapsible shelves, typewriter-supporting boards for desks, and the like, when brought into a 20 predetermined position.

The primary object of the invention is to provide a latch mechanism which will automatically secure and sustain the supporting board, or the like when it has been moved to 25 a point just past its operative position and has then been returned to operative position, but which will release the supporting board when it has subsequently been moved away from its operative position in the same direction as in the first instance but to a 30 greater extent, so that upon movement thereafter toward its inoperative position the board will be free from obstruction by the latch mechanism.

35 The improved device is shown in the accompanying drawings, in which:

Figure 1 is a perspective view of a portion of a typewriter cabinet or desk and a portion of the supporting board for a 40 appearing typewriting machine, the board being shown partly in section and the improved latch mechanism being shown mounted upon the cabinet and operatively engaged with the supporting board, the board being 45 at the limit of its initial movement past its operative position; and, Fig. 2 is a similar view, showing the relative positions of the different parts of the latch mechanism when the supporting board has been lowered into 50 its operative position after the initial movement thereof, the limiting member being in its inoperative position, the locking pawl being inoperative engagement with the supporting board, and the sliding piece carried

by the locking pawl being locked in its retracted position.

The lock mechanism is composed of the main parts A, B, C, D, E, F, and G. One of these devices is placed on the post 26 on each side of the case.

The sector A is pivotally mounted at a^1 , its rotation being limited by the pin a^3 and the slot a^2 . On its outer lower edge, a notch or groove a^4 is provided into which the pin b^1 of one arm of the bell crank lever B, 60 which is pivotally mounted at b^2 , catches. The second arm b^3 of this lever B is connected by means of a connecting rod C, to a sliding piece D, said rod C being connected to a side projection d^3 of this sliding piece 65 D. The sliding piece D is guided by two pins e^1 , e^2 which engage the slots d^1 , d^2 respectively, so that the sliding piece D can move in a straight line relatively to the arm or locking pawl E, on which the pins e^1 , e^2 are 70 fastened. The sliding piece D moreover possesses at its lower end a hook or pawl d^5 . The head d^4 and the hook or pawl d^5 of the sliding piece D are arranged in a straight line with the guiding slots d^1 , d^2 . Finally, 80 a spiral spring d^6 is attached to the side projection d^3 , which spring is fastened at its upper end to the locking pawl E at e^3 . This locking pawl E pivots about the journal e^4 and is continuously drawn by a spiral 85 spring e^5 against the two pins g^1 , g^2 , of the disk G. For this purpose, the upper portion of the locking pawl E is provided with two straight bearing surfaces e^6 , e^7 , which correspond to the pins g^1 , g^2 . The turning of 90 the locking pawl E is also limited by a slot e^8 and a pin e^9 .

Opposite the hook or pawl d^5 of the sliding piece D, a spring-controlled pawl F is arranged, which, being subject to the pressure of the spring f^2 , tends to turn around the journal f^1 in a counter clockwise direction, being limited in this turning by a fixed stop f^3 . The disk G which carries two pins g^1 , g^2 is pivotally mounted on the fixed journal g^3 and said disk G is formed with a head g^4 , which in the position of rest of the lock mechanism is situated above the head d^4 of the sliding piece D.

On each side of the supporting board 2 105 to be locked, there is a catch or stop 24, which acts in connection with the head d^4 of the lock mechanism. During the upward

movement of the supporting board 2, the catch or stop 24 strikes the side of the head d^4 which yields sidewise, and as soon as the stop 24 has passed, snaps back into its original position under the pressure of the spring e^5 . The upward movement of the supporting board 2 is limited by the sector A in the position shown in Fig. 1. If, either by the exertion of slight pressure on the supporting board of the machine, or by any means, the board 2 with its catch or stop 24 is now slightly lowered, the said catch carries down with it the sliding piece D and the hook or pawl d^5 catches in the corresponding hook of the pawl F.

When the hook d^5 has once caught in the pawl F, no further downward movement of the board is possible, as the head d^4 cannot move out of the path of the catch 24, as the pins e^1 and e^2 are at the top of the slots d^1 , d^2 , and thus prevent the sliding piece D from moving farther downward. The board 2 is thus secured in the position shown in Fig. 2. The slight sinking of the supporting board 2, and the downward motion, thereby produced, of the sliding piece D over the guiding pins e^1 , e^2 in the slots d^1 , d^2 is transmitted by the rod C to the bell crank lever B, which consequently turns in a clockwise direction and carries the sector A around to the right, so that this is drawn back out of the path of the supporting board 2, and no longer limits this in its upward motion.

If it is desired to return the board, all that is necessary is to raise the supporting board 2 slightly, so that it passes the sector A, which is drawn back sidewise, and the catch or stop 24 strikes the under side of the head g^4 of the disk G, turns the latter around the journal g^3 , and moves beyond the head g^4 .

As soon as the catch or stop 24 has passed by the head g^4 , the disk G is turned back again toward the left by the action of the spring e^6 , transmitted by the bearing surface e^7 to the pin g^2 , so that the head g^4 is below the catch or stop 24. When the supporting board 2 is lowered again, the head g^4 is turned downward by the catch or stop 24, the pin g^1 through contact with the bearing surface e^6 swinging the arm E out to such an extent that the hook d^5 is lifted out of the pawl F. But as soon as this is released, the sliding piece D moves upward by the action of the spring d^8 until the upper edge of the head d^4 is above the catch or stop 24, so that the latter with the supporting board may move farther down unhindered. As the sector A is swung again toward the left by the snapping back of the sliding piece D, all the parts of the lock mechanism are once more in the initial position (Fig. 1).

Having now particularly described and ascertained the nature of the said invention

and in what manner the same is to be performed, we declare that what we claim is:—

1. In an article of furniture, in combination, a supporting member mounted for movement between its inoperative and operative positions, and a latch for securing the supporting member in operative position comprising a locking pawl adapted to engage a part of the supporting member after initial movement of the same past its operative position to a certain extent, means for limiting the movement of the supporting member in this direction normally to the extent mentioned, means for rendering the said limiting means inoperative upon return of the supporting member to operative position, and means adapted to be actuated by the said member after movement of the same for a second time and to a greater extent in the same direction past operative position and upon return movement thereof for moving the locking pawl into inoperative position clear of the said member as the latter moves past the pawl toward its inoperative position.

2. In an article of furniture, in combination, a supporting member mounted for movement between its inoperative and operative positions, and a latch for securing the said member in its operative position comprising a movable locking pawl, a sliding piece mounted upon the pawl for limited movement relative thereto, means for yieldingly maintaining the sliding piece normally in operative position projecting from the pawl for contact with the supporting member, the said member when in operative position in engagement with the pawl being adapted to bear against the sliding piece to maintain the same in retracted position, a movable limiting member adapted to normally project into the path of the supporting member at a position more remote from the inoperative position of the supporting member than its operative position, means for transmitting motion from the sliding piece of the pawl to the said limiting member to render the latter inoperative upon movement of the said piece into retracted position, and a movable releasing device for the locking pawl disposed normally so that it projects into the path of a part of the supporting member but is shielded from contact therewith by the limiting member when operative.

3. In an article of furniture, in combination, a supporting member mounted for movement between its inoperative and operative positions, a latch for securing the said member in its operative position comprising a movable locking pawl, a sliding piece mounted upon the pawl for limited movement relative thereto, means for yieldably maintaining the sliding piece normally in operative position projecting from the pawl

for contact with the supporting member, the said member when in operative position in engagement with the pawl being adapted to bear against the sliding piece to maintain the same in retracted position, a movable limiting member adapted normally to project into the path of the supporting member at a position more remote from the inoperative position of the supporting member than its operative position, means for transmitting motion from the sliding piece of the pawl to the said limiting member to render the latter inoperative upon movement of the said piece into retracted position, a movable releasing device for the locking pawl disposed normally so that it projects into the path of a part of the supporting member but is shielded from contact therewith by the limiting member when operative, and yieldable means for normally maintaining the locking pawl in operative position.

4. In an article of furniture, in combination, a supporting member mounted for movement between its inoperative and operative positions, and a latch for securing the said member in its operative position comprising a movable locking pawl, a sliding piece mounted upon the pawl for limited movement relative thereto, means for yieldably maintaining the sliding piece normally in operative position projecting from the pawl for contact with the supporting member, the said member when in operative position in engagement with the pawl being adapted to bear against the sliding piece to maintain the same in retracted position, a movable limiting member adapted normally to project into the path of the supporting member at a position more remote from the inoperative position of the supporting member than its operative position, means for transmitting motion from the sliding piece of the pawl to the said limiting member to render the latter inoperative upon movement of the said piece into retracted position, a movable releasing device for the locking pawl disposed normally so that it projects into the path of a part of the supporting member but is shielded from contact therewith by the limiting member when operative, and a second pawl adapted to engage the sliding piece on the first named pawl automatically upon movement of the said piece into retracted position while the first pawl is in operative position, the said piece being adapted to be moved out of engagement with the second pawl to be released upon movement of the first pawl into inoperative position.

5. In an article of furniture, in combination, a supporting member mounted for movement between its inoperative and operative positions, and a latch for securing the said member in its operative position comprising a movable locking pawl, a sliding piece mounted upon the pawl for limited movement relative thereto, means for yieldably maintaining the sliding piece normally in operative position projecting from the pawl for contact with the supporting member, the said member when in operative position in engagement with the pawl being adapted to bear against the sliding piece to maintain the same in retracted position, a movable limiting member adapted normally to project into the path of the supporting member at a position more remote from the inoperative position of the supporting member than its operative position.

55

6. In an article of furniture, in combination, a supporting member mounted for movement between its inoperative and operative positions, and a latch for securing the said member in its operative position comprising a movable locking pawl, a sliding piece mounted upon the pawl for limited movement relative thereto, means for yieldably maintaining the sliding piece normally in operative position projecting from the pawl for contact with the supporting member, the said member when in operative position in engagement with the pawl being adapted to bear against the sliding piece to maintain the same in retracted position, a movable limiting member adapted 70 normally to project into the path of the supporting member at a position more remote from the inoperative position of the supporting member than its operative position, means for transmitting motion from the sliding piece of the pawl to the said limiting member to render the latter inoperative upon movement of the said piece into retracted position, a movable releasing device for the locking pawl disposed normally so that it projects into the path of a part of the supporting member but is shielded from contact therewith by the limiting member when operative, and a second pawl adapted to engage the sliding 75 piece on the first named pawl automatically upon movement of the said piece into retracted position while the first pawl is in operative position, the said piece being adapted to be moved out of engagement with the second pawl to be released upon movement of the first pawl into inoperative position.
